UNITED STATES PATENT OFFICE.

SEBASTIAN SCHÄDLE, OF GRÖNENBACH, GERMANY.

CYCLE-LOCK.

SPECIFICATION forming part of Letters Patent No. 623,184, dated April 18, 1899.

Application filed January 21, 1898. Serial No. 667,445. (No model.)

To all whom it may concern:

Be it known that I, SEBASTIAN SCHÄDLE, of Grönenbach, near Allgäu, in the Empire of Germany, have invented Improvements in 5 Cycle-Locks, of which the following is a specification, reference being had therein to the accompanying drawings.

This invention relates to an improved cycle-lock for preventing the cycle from being 10 used by unauthorized persons, the construction of said lock being such that a bolt projecting from the lock stops one of the two 15 pedal-cranks, and thus prevents the whole pedal mechanism from executing the slightest movement.

The invention is represented in the accompanying drawings, in which—

Figures 1 and 2 are different horizontal sections. Fig. 3 is a vertical section through 20 the lock; Fig. 4, an upper view of the lock, while Figs. 5 and 6 illustrate the method in which the lock is arranged on the velocipede.

In the interior of the lock a bolt *a* is arranged which so projects from the lock that 25 when being slid forward it will grip one of the cranks *b*, and thus prevent either of the cranks from further rotation. This bolt is slid in and out by hand, and the point in question solely is to retain the bolt in either 30 of its positions and to prevent the bolt when in the closed position from being moved back by unauthorized persons. For this purpose in the interior of the lock a tumbler *d*, capable of turning on a pivot *c*, is arranged, against 35 the nose *e* of which bears the bolt *a* when in either of its extreme positions. Through the action of a spring *g* the tumbler *d* is constantly pressed against the bolt, so that the latter can only be brought into the open or 40 closed position if the tumbler *d* has been properly moved back—that is to say, brought into the position shown in dotted lines in Fig. 1.

The drag-bar *h* may be actuated so as to 45 move aside the pin *i*, which is fixed to the tumbler *d*, and thus simultaneously shift the said tumbler *d*. This drag-bar *h* is rotatable upon a transverse fence-bar *k*, which can be moved between the guides *l*, and which is 50 moved by means of a knob *m*, projecting from the lock-casing. The limits of movement of the knob is determined by the angular slot

n, arranged in the upper casing of the lock, from which the said knob projects, the operation being such that the knob is first moved 55 out of its highest position into that represented in Fig. 4 and is subsequently moved toward the left. By the latter portion of the movement the drag-bar *h* is turned toward the left, and simultaneously therewith also 60 the tumbler *d*, retaining the bolt, is moved toward the left.

It is evident that the knob must first be turned out of its initial position into the knee of the slot before it can execute the left-hand 65 movement by which the tumbler *d* is moved.

The principal idea on which the invention is based is that the movement of the knob out of its initial position down to the knee of the slot can only be executed when the four 70 hands *r* occupy a certain relative position. Now as, on the one hand, very many combinations are possible with these four hands and as, on the other hand, only the owner of the cycle is aware of the position required for 75 placing the lock into its opening position it is evident that for any unauthorized person it is next to impossible to open the lock. Each of the hands is connected to a disk or tumbler *o*, each of which latter is provided with 80 a gating *s*, Figs. 2 and 3. The connection between the hands and the tumblers is of course such that one hand is connected with one tumbler by means of an axle, while the other hand, turning about the same axle, is connected 85 with the second tumbler by means of a small tube or sleeve traversed by the before-mentioned axle. The fence-bar *k*, hereinbefore referred to, is provided with two fences *t*, which are enabled to engage with the gatings *s* of 90 the tumblers. The said fence-bar *k* thus can only be moved downward to such an extent that the fences come into contact with the peripheries of the tumblers. Consequently 95 the knob *m*, connected to the fence-bar by means of the drag-bar *h*, is prevented from being slid down to the knee of the slot and accordingly the pivotal tumbler *d* cannot be moved out of its locking position. After each displacement of the bolt *a* the tumbler *d* is returned to its locking position, Fig. 1, by a 100 corresponding rotation of the drag-bar *h*. Thus the movement of the bolt *a* required for locking as well as for releasing the wheel can

only be effected if the hands are so placed that the gatings of the tumblers lie opposite the two fences *t*. This given position of the hands may of course be altered by displacing them upon their axes or by imparting to them another relative position on mounting them upon their axes.

5 The lock admits of being very rapidly opened and closed by passing the four hands 10 into the proper predetermined position, only known to the owner of the cycle. The main advantage of the lock, however, consists in the fact that no key is required for opening and closing the lock, so that the cyclist is not exposed to the inconvenience of losing his key.

15 What I claim, and desire to secure by Letters Patent of the United States, is—

1. A cycle-lock comprising a locking-bolt mounted in a suitable casing, a pivoted tumbler mounted in the said casing and adapted 20 to engage the inner end of the said bolt for holding the same in place, a drag-bar for moving the said pivoted tumbler out of engagement with the bolt, and means for preventing the movement of the drag-bar, substantially as described.

2. In a cycle-lock, the combination with a bolt mounted in a suitable casing, of a pivoted tumbler mounted therein and adapted 30 to engage the inner end of the said bolt for holding it in its extreme positions, a drag-bar also pivotally mounted in the said casing and adapted to have a radial movement in order to engage the said tumbler for moving it out 35 of engagement with the bolt, and means for preventing the movement of the drag-bar when the bolt is in its locked position, substantially as described.

3. In a cycle-lock, the combination with a 40 suitable bolt, of a pivoted tumbler for engaging and controlling the said bolt, a fence-bar also mounted in the said casing, a drag-bar pivoted to said fence-bar and adapted to engage the pivoted tumbler for releasing the bolt, 45 and means for controlling the movement of the fence-bar, substantially as described.

4. In a cycle-lock, the combination with a bolt, of a tumbler for controlling the same, a fence-bar carrying fences, a drag-bar pivoted 50 to said fence-bar and adapted to swing upon said pivotal point to operate the said tumbler, and permutation-tumblers for controlling the movement of the fence-bar, substantially as described.

5. In a cycle-lock, the combination with a 55 suitable casing, of a bolt adapted to move therein, the outer end of the said bolt being provided with engaging arms for engaging the crank of the cycle when the bolt is in its outward position, a pivoted tumbler in the 60 said casing adapted to engage the rear end of the said bolt for holding it in its extreme positions, a drag-bar pivotally mounted in the said casing and having a stud which projects exteriorly thereof through a slot formed 65 in the said casing, the said slot being approximately L-shaped, whereby the stud upon the said bar must be brought to the lower portion of the slot before it can move laterally for engaging the pivoted tumbler, and means connected to the drag-bar for engaging notched tumblers, the construction being such that when the said means engages the said notches, the stud and arm may be moved so as to swing laterally for disengaging the bolt of the lock, 70 substantially as described.

6. In a cycle-lock, the combination with a suitable bolt, of a pivoted tumbler for controlling the same, a fence-bar provided with two or more fences, a drag-bar pivotally 80 mounted on the said fence-bar, and permutation-tumblers provided with gatings and adapted to engage the fences, and means for preventing the movement of the drag-bar upon its pivotal point when the fences are 85 out of engagement with the said gatings, substantially as described.

7. In a cycle-lock, the combination with a suitable bolt, of a tumbler for controlling the same, a fence-bar carrying fences, a drag-bar 90 pivoted to the said fence-bar and adapted to operate the said tumbler, permutation-tumblers having gatings, exterior pointers secured to said permutation-tumblers for indicating their position, and a projection formed upon 95 the said drag-bar adapted to engage a slot formed in the casing, the construction being such that the drag-bar cannot be moved so as to operate the bolt-tumbler except when the gatings of the permutation-tumblers are 100 in a position to receive the fences of the fence-bar, substantially as described.

In witness whereof I have hereunto set my hand in presence of two witnesses.

SEBASTIAN SCHÄDLE.
